[57] **CLAIM**

The ornamental design for a combined transmitter and receiver for satellite communication systems, as shown.

DESCRIPTION

FIG. 1 is a front, top and left side perspective view of a combined transmitter and receiver for satellite communication systems showing our new design;

FIG. 2 is a rear, top and right side perspective view thereof;

FIG. 3 is a right side elevational view thereof;

FIG. 4 is a top plan view thereof;

FIG. 5 is a left side elevational view thereof;

FIG. 6 is a front elevational view thereof;

FIG. 7 is a bottom plan view thereof; and,

FIG. 8 is a rear elevational view thereof.

FIG. 1

FIG. 2

FIG.3

FIG.4

FIG.5

FIG. 6

FIG. 7

FIG. 8
